DESIGN FOR A DRAPED PARTITION OR SIMILAR ARTICLE

Morris Lange, Cleveland, Ohio

Application September 1, 1938, Serial No. 79,662

Term of patent 7 years

To all whom it may concern:

Be it known that I, Morris Lange, a citizen of the United States, residing at 2874 Mayfield Road, in the city of Cleveland, county of Cuyahoga, and State of Ohio, have invented a new, original, and ornamental Design for a Draped Partition or Similar Article, of which the following is a specification, reference being had to the accompanying drawing, forming a part thereof.

Figure 1 is a front elevation of the draped partition; and Figure 2 is a diagrammatic view taken substantially along the lines 2—2 of Figure 1.

I claim:

The ornamental design for a draped partition or similar article, substantially as shown.

MORRIS LANGE.
